UNITED STATES PATENT OFFICE.

GEORGE W. SHOTWELL, OF BROADHEAD, WISCONSIN, ASSIGNOR OF ONE-HALF TO G. W. CRONK, OF SAME PLACE.

SPRING BED-BOTTOM.

SPECIFICATION forming part of Letters Patent No. 259,594, dated June 13, 1882.

Application filed April 11, 1882. (No model.)

To all whom it may concern:

Be it known that I, GEORGE W. SHOTWELL, of Broadhead, in the county of Green and State of Wisconsin, have invented certain new and useful Improvements in Spring Bed-Bottoms; and I do hereby declare the following to be a full, clear, and exact description of the invention, such as will enable others skilled in the art to which it pertains to make and use it, reference being had to the accompanying drawings, which form part of this specification.

My invention relates to an improvement in spring bed-bottoms; and it consists in the combination of a cover made of any suitable textile fabric, which is spread over the tops of the springs, and which has its edges secured to coil springs which extend the full length of the bed, as will be more fully described hereinafter.

The object of my invention is to provide a means whereby the edges of the bed can be kept up as perfectly as the center, and thus decrease the number of springs required.

Figure 1 is a plan view of my invention. Fig. 2 is a side elevation of the same, partly in section.

A represents a suitable bedstead of any desired construction; B, the slats; and C the springs, which are secured thereto in the usual manner. Spread over the tops of the springs is the cover D, which is made of any suitable textile fabric, and which has its edges at-

tached in any suitable manner to the two coiled springs F, which extend the full length of the bed. The ends of these two springs F are attached to the bedstead by any suitable fastenings. These springs serve to keep the cover stretched tightly across the springs and to prevent the edge of the bed from being mashed or broken down, as is generally the case. As 35 these springs extend along the full length of the bed and under the edges of the mattress, these edges will be kept up as evenly in place as the center of the bed, and thus a more even surface will be preserved. By this construction 40 a much smaller number of springs C can be employed and as good a result obtained as where a much larger number of springs are used for the purpose of supporting the edges of the bed.

Having described my invention, I claim—
In a spring bed-bottom, the combination of the bedstead, the slats B, the springs C, cover made of any textile material, and the coiled springs to which the edges of the cover are 45 attached, substantially as shown and described.

In testimony whereof I affix my signature in presence of two witnesses.

GEORGE W. SHOTWELL.
